UNITED STATES PATENT OFFICE

2,026,381

HIGH VOLTAGE PRIMARY CUT-OUT

George H. Fiedler, Rochester, N. Y., assignor to
 General Electric Company, a corporation of
 New York

Application March 13, 1934, Serial No. 715,312

4 Claims. (Cl. 200—121)

My invention relates to high voltage primary cut-outs and has for its object the provision of indicating means for indicating the condition of the circuit through the cut-out.

5 Another object of my invention is to provide indicating means for enclosed fuse cut-outs which will indicate an open circuit through the cut-out while maintaining the cut-out and the casing cover in their respective normal operating 10 positions.

For a better understanding of my invention, together with other and further objects thereof, reference is had to the following description, taken in connection with the accompanying 15 drawing, and its scope will be pointed out in the appended claims.

The accompanying drawing illustrates a sectional side view of a high voltage primary cut-out for outdoor use equipped with a signaling device built in accordance with my invention. The 20 signaling device is shown in its closed-circuit indicating position in full lines and in its open-circuit indicating position in dotted lines.

Referring to the drawing in detail, the cut-out 25 comprises mainly an enclosing casing 1 which contains the stationary contact clips 2 and 3 for a fuse 4 and a closing cover 5 which supports the fuse and moves it into engagement with the contact clips 2 and 3 when the cover is moved into 30 closing position on the casing 1.

The casing 1 comprises a rectangular receptacle made of thick porcelain and cast into a single piece. The casing is open in front and is provided with two petticoat insulators 6 and 35 7 cast integral with the back of the casing, by means of which the casing may be conveniently mounted. The contact clips 2 and 3 are respectively mounted on bosses 8 and 9 projecting from the back in the casing. The clips may be mounted 40 on the bosses in any convenient manner. The particular method illustrated comprises a collar 11, wedged into a hole 12 in the boss, into which the screw 13 is turned. Cables to the clips may be brought into the casing through two conduits 45 14 and 15 in the side of the casing and may be attached respectively to the cable terminals 16 and 17 which are connected to the clips and are supported adjacent the inner ends of the conduits. The cable terminal 16 is attached to a terminal strip 18 by a screw 19, which in turn is held in contact with fuse clip 2 by a screw 13. The terminal 17 is attached similarly to a terminal strip 20 by a screw 21 and the strip 20 is held in contact with clip 3 by another screw 13.

55 The fuse 4 is mounted on the cover 5 by means

of a spring clip 23 which engages the lower section of the fuse and a collar 24 which engages the upper end of the fuse 4. The spring clip 23 is similar to the clips 2 and 3 and simply engages the lower part of the fuse. It is attached to the 5 cover 5 in any convenient manner. The collar 24 is mounted upon a boss 26 projecting inwardly from the cover and is attached thereto by means of a tongue 27 projecting from the collar at approximately 45°. The surface of the boss 26 being vertical, the collar 24 is positioned about 45° to the normal operating position of the fuse when it is so attached. This construction provides an easy method of mounting the fuse on the cover. In order to mount the fuse, it is only 10 necessary to insert the upper end of the fuse into the collar 24 while holding the fuse at approximately 45° to the cover and then moving the lower end of the fuse inwardly into engagement with the clip 23. This movement brings the 15 outer end of the fuse into intimate contact with the edges of the collar and is held there by a U-shaped spring 28 which is mounted underneath the collar tongue and exerts pressure against the 20 fuse.

The cover which may be either hooked or hinged at the bottom may be forced into position by means of an integral loop 29 cast upon the upper front portion of the cover. When the cover is in this position the casing 1 is completely 25 closed and the fuse 4 is simultaneously moved into engagement with the spring clips 2 and 3.

In accordance with my invention, the cover 5 is provided with a signaling vane 30 comprising a plate of any convenient material and preferably approximately the area or size of the cover 5. It is provided at its lower end with a pair of arms 31 projecting vertically from the vane over the edges of the cover 5. The arms are pivoted by means of pivot screws 32 on the cover so 35 that the vane may be held in a vertical position parallel to the cover 5 or in a horizontal position at right angles to the cover. An opening 33 is provided in the vane so that the loop 29 may project therethrough and permit the mounting of 40 this vane close to the cover.

The signaling vane 30 is further provided with a latch hook 34 which projects through a hole 35 in the cover 5 when the vane is parallel to the cover. This hook projects through the cover 50 and engages a latch 36, which in turn is pivoted on an arm 37 mounted on the inside of the cover 5. The latch 36 is normally moved upwardly against a stop 38 by a spring 40. In this position, the latch 36 engages the hook 34. The latch 55

may be tripped by a latch arm 41 which extends over the upper end of the fuse 4 and is operated by a plunger 42 which moves upwardly when the fuse circuit is broken.

- 5 6 The fuse 4 is of the refillable expulsion type and is provided at its upper end with a spring-operated plunger 42. It comprises an insulating tube 43 containing the fuse link 44 which is attached at its respective ends to leads 45 and 46. 10 10 The lead 45 is attached to a metal contact sleeve 47 at the lower end of the fuse and is locked thereto by a collar 48. The lead 46, which is preferably rigid, is attached to a disk 50. The disk 50 is mounted in a sliding sleeve 51 within 15 15 the upper contact sleeve 52 of the fuse. The slideable sleeve 50 is provided intermediate its ends with a web through which the lead 46 and an insulating tube 53 project into the fuse sleeve 43. The plunger 42 is screwed into the upper end of 20 20 the sliding sleeve and clamps the disk 50 between itself and the web. The contact sleeve 52 is screwed on to the upper end of the fuse sleeve 43 and is also provided with a web through which the insulating tube projects. When the 25 25 fuse link 44 is intact, the sliding sleeve 51 is moved downwardly against the pressure of a spring 54, the sleeve 51 being pulled down inside of the contact sleeve 52 until a slight shoulder on the sleeve engages the end of the contact 30 30 sleeve 52. A thimble provided with an opening through its top is screwed over the end of the contact sleeve so that when the plunger and sliding sleeve are in this position the end of the plunger is flush with the thimble. When the 35 35 fuse link 44 then breaks the plunger is moved upwardly into engagement with the tripping arm 41 of the latch 46 and thus disengages the hook 34. This enables a spring 55 on the vane to move the signaling vane into the horizontal position indicated in dotted lines in the drawing. 40 40

In operation the fuse 4, with the plunger retracted, is mounted on the cover and the signaling vane is latched into the position parallel to the face of the cover. The fuse and cover are then moved into the operating position where the fuse engages the contacts and the cover closes the casing and protects the fuse and the contacts. When the fuse link breaks, due to an overload or any other reason, the plunger trips the latch and the signaling vane drops into its horizontal position. My invention, therefore, provides a simple method of indicating the condition of an enclosed fuse without interfering with the protecting casing.

What I claim as new and desire to secure by Letters Patent of the United States, is:

1. In a cut-out device, the combination of a fuse, a casing therefor, a cover for said casing, a signaling member having substantially the same area as said cover pivoted upon said cover, means for maintaining said signaling member in a position parallel to said cover when the said fuse is operative, and means operated when said fuse breaks for moving said signaling member into a second position below said cover, whereby the said cover is substantially concealed in the first position of said member and exposed at the second position thereof.

2. In a primary cut-out, the combination of an outdoor casing provided with stationary contacts, a cover for said casing, a fuse supported thereby and moved into engagement with said contacts when said cover is in position to close said casing, a signaling member comprising a vane having substantially the same area as said cover pivoted on said cover, means for maintaining said member in one signaling position parallel to said cover when the said fuse is operative, and means operated when said fuse breaks for moving said member into a second signaling position substantially at right angles to said cover whereby the cover is concealed in the first position of said member and exposed in the second position thereof.

3. In a cut-out device, the combination of a fuse provided with a fuse link, a casing provided with contact clips for engaging said fuse, a cover for said casing provided with means for supporting said fuse and for moving it into engagement with said contact clips, a signaling vane pivoted upon the outside of said cover and provided with a latch hook, a latch supported upon the inner side of said cover for engaging said hook and thereby holding said vane in one position, and means operated when said fuse link breaks for operating said latch and moving said signaling vane into a second position.

4. In a primary cut-out device, the combination of a casing and a cover therefor, a signaling member pivoted on the outside of said cover, latching means provided on the inside of said cover for holding said signaling member in one position, and a fuse mounted within said casing provided with a fuse link and a retractile plunger for operating said latch and moving said signaling member to a second position when said fuse link breaks.

GEORGE H. FIEDLER.
